BORING APPARATUS

Timothy F. Sullivan, San Francisco, Calif.

Application October 6, 1933, Serial No. 692,406

3 Claims. (Cl. 255—4)

This invention relates to improvements in boring apparatus of the kind adapted for use in drilling wells or holes in the earth.

The primary object of my invention is to provide improved boring apparatus of the kind characterized, embodying a novelly constructed boring tool, an air motor for rotating the tool and a dirt receiving bucket positioned directly above the tool.

10 Another object of my invention is to provide improved boring apparatus of the kind characterized which embodies novel means associated with an air motor for centering the boring tool and for preventing the rotation of the motor casing during the boring operation.

15 A further object of my invention is to provide improved boring apparatus for use in drilling wells, having a novel dirt receiving bucket which is provided with detachable means permitting the convenient emptying thereof.

20 A still further object of my invention is to provide improved boring apparatus of the kind characterized which is simple and sturdy in construction, easy to assemble and repair, reliable under conditions of hard service, and mechanically efficient in operation.

25 Other objects more or less apparent will present themselves or will be specifically pointed out in the description to follow.

30 In the accompanying drawing:

Fig. 1 is a side elevation of boring apparatus constructed in accordance with my invention, showing the associated tubular casing in vertical section;

35 Fig. 2 is a section taken on line 2—2 of Fig. 1;
Fig. 3 is a section taken on line 3—3 of Fig. 1;
Fig. 4 is a section taken on the line 4—4 of Fig. 1 and;

40 Fig. 5 is a section taken on the line 5—5 of Fig. 2.

45 Referring to the drawing the numeral 1 indicates a tubular metallic casing, the sections of which are ordinarily lowered step by step as the drilling or boring operation progresses downwardly into the earth. The inside surface of the casing is provided with inwardly projecting vertical ribs 2 at opposite sides, while its outside surface at certain intervals is provided with outwardly disposed projections or fins 3, which ordinarily extend into the earth and prevent the casing from turning during the drilling operation. Welded or otherwise secured to the beveled lower end of the casing is an annular cutter 4 having a sharp lower edge which permits the casing to be driven downwardly into the hole

drilled by the boring tool. Suitably secured, as by welding, to the inside of the casing at its lower end is an inwardly projecting annular member 5, the purpose of which will be herein-after described.

5 Suspended by a cable 6 within the casing 1 from a windlass or other suitable hoisting means, is a motor 7, of the type operated preferably by compressed air. Compressed air from a suitable source is ordinarily supplied to the motor by a flexible conduit 8, and a similarly constructed conduit 9 carries the discharged air from the motor to the outer atmosphere. Should it be desired to operate the motor in a reverse direction the conduit 9 may be employed to supply the compressed air to the motor, and the conduit 8 to carry it therefrom.

10 The motor casing is considerably smaller in circumference than the casing 1, thereby permitting the rapid and convenient lowering and raising thereof. Extending outwardly from opposite sides of the motor casing are members 10 which preferably have adjustable end pieces 11 screwed onto their outer ends. The end pieces are adapted to engage with the vertical ribs 2 of the casing and thereby prevent the motor from rotating during the boring or drilling operation. In the event either smaller or larger size casings are employed, the end pieces 11 may be screwed inwardly or outwardly so the members 10 are 15 shortened or lengthened, thereby permitting the use of the same motor with different size casings. The projecting members 10 not only serve to prevent the turning of the motor but they also function to center the boring tool with reference to opening through the casing and to cause the motor and the said tool to move downwardly in a straight path.

20 Suitably connected to the operating mechanism of the motor 7 is a shaft 12, preferably square in cross-section, and provided at its lower end with a detachable boring tool generally designated by the numeral 13. The boring tool is made up of a cone-shaped auger 14, outwardly extending inclined cutters 15 which are bolted 25 to radially disposed inclined supports 16, and curved deflector plates 17 also bolted to the supports.

25 Adjustably secured to the shaft 12 as by set screws, are two spaced collars 18, between which 30 is mounted the hub of a spider 19. The outwardly disposed arms of the spider are affixed to the top edge of a bucket 20, the bottom edge of the said bucket being disposed adjacent and around the lateral edge of the deflector plates 35

17 of the boring tool 13. The deflector plates and the cutters 15 of the boring tool form a bottom for the bucket and serve as supporting means for the dirt which is actuated in an upward direction into the bucket by the said boring tool. The bucket 20 and the spider 19 are made in two sections which are hinged together by hinges 21. Suitable fastening means 22 serves to detachably maintain the disconnected edges of the said sections in close proximity with one another, thereby holding the two parts of the spider 19 in such a position that its hub normally extends around the shaft 12 with its underneath surface resting on the lower of the two collars 15. After the bucket has been filled with dirt which has resulted from the operation of the boring tool rotating in the earth, and the apparatus has been raised above the surface of the ground by reeling in the cable 6, the bucket can be easily emptied by unfastening the fastening means 22 and opening the two sections.

The combined weights of the motor 7 and the bucket 20 ordinarily produce sufficient downward pressure against the boring tool 13 to make the drilling operation successful in most kinds of earth formations. When the bore has reached such a depth that the projecting members 10 of the motor 7 encounter the annular member 5 of the casing, the ordinary practice is then to raise and empty the bucket and to drive the casing down to a point where the cutter 4 encounters the bottom of the said bore.

It is apparent to those skilled in the art that my invention is susceptible of numerous modi-

fications in regard to form, shape and minor details of construction. It is therefore to be understood that the appended claims are to determine the scope of my invention rather than the exact disclosures made herein.

Having described my invention what I claim is:

1. In boring apparatus, a motor provided with a rotatable shaft, a boring tool secured to the shaft, and a bucket secured to the shaft and located above the tool, the said bucket being formed in two sections which are hinged together, each of the said sections having a spider construction, the hubs of which extend around the shaft. 5

2. In boring apparatus, the combination of a boring tool, a rotatable shaft to which the tool is secured, and a tubular bucket supported by the shaft and positioned to receive material forced upwardly by the tool, the said bucket being comprised of a plurality of sections pivotally joined together each of the said sections having rigid spider members secured thereto, the said spider members having hub forming parts thereon which rest on supporting means carried by the shaft. 10

3. In boring apparatus, the combination of a motor having a shaft, a boring tool secured to the shaft, a bucket mounted on and extending around the shaft, the bottom edges of the bucket being positioned around and adjacent the tool and the top end of the said bucket being formed with a spider construction, the hub of which spider construction detachably embraces the shaft. 20

TIMOTHY F. SULLIVAN.
